UNITED STATES PATENT OFFICE.

CHARLES E. RICHARDSON, OF MINNEAPOLIS, MINNESOTA.

DOOR.

SPECIFICATION forming part of Letters Patent No. 443,541, dated December 30, 1890.

Application filed March 4, 1890. Serial No. 342,670. (No model.)

To all whom it may concern:

Be it known that I, CHARLES E. RICHARDSON, a citizen of the United States, residing at Minneapolis, in the county of Hennepin 5 and State of Minnesota, have invented a certain new and useful Improvement in Doors, of which the following is a full, clear, and exact description.

The object of this invention is to provide a 10 double paneled sheet-metal fire-proof door for dwelling-houses and the like buildings, which is of simple, economical, and durable construction.

The invention consists of an interior door 15 composed of a frame or core of wood or equivalent material, an outer covering or casing comprising two like or similar sections of sheet metal entirely concealing the wooden frame or core, and means for securing said 20 metal sections to the wooden frame or core, substantially as hereinafter more particularly set forth and claimed.

In the accompanying drawings, illustrating my invention, in the several figures of which 25 like parts are similarly designated, Figure 1 is an elevation. Fig. 2 is a vertical section taken in the plane of line $\alpha\alpha$, Fig. 1. Fig. 3 is an elevation of the wooden frame or core. Fig. 4 is a detail showing the preferred manner 30 in which the metal sections are secured to the frame or core. Fig. 5 is an edge view of the finished door, and Fig. 6 is an edge view of the wooden frame or core.

A door constructed in accordance with my 35 invention consists of a wooden frame or core, which, as herein shown, is composed of the uprights $a a$, end pieces $b b$, and a central cross-piece c , all of which are suitably jointed, (see Fig. 3,) and upon this frame or core is 40 secured the exterior covering or casing, which consists of two like or similar sections $d d$, of sheet metal, preferably steel, said sections being stamped, rolled, or pressed into any desired design and configuration of paneling 45 d' . After these metal sections d are thus stamped, rolled, or pressed into the desired shape the edges thereof are bent at right angles to form flanges e , which serve to conceal the edges of the wooden frame, and also aid 50 in securing the metal sections to the frame or core. One of these metal sections d is placed upon each side of the frame or core, and the

flanges e of said sections are fitted over and upon the sides and ends of the frame and are fastened thereto by means of screws or nails. 55

In Fig. 4 of the drawings I have shown the preferred form of fastening for securing the metal sections upon the frame or core, which is as follows: The uprights $a a$ and end pieces $b b$ of the wooden frame or core are provided 60 on their outer faces with grooves f , into which the flanges e of the metal sections are forced or bent, as at g , and in these grooves and upon the flanges thus bent or forced therein I secure metal strips h , which are provided at 65 suitable intervals with holes or openings to receive screws i or other fastening devices, and these metal strips h are of such size and shape as to fit snugly into the grooves f and be flush with the edges of the door. 70

The door thus constructed may be painted or otherwise finished, so as to have the appearance of an ordinary wooden door.

I have herein shown the metal sections d as constructed of a single piece of sheet metal; 75 but I wish to be understood as not limiting my invention to this exact construction, as each section may be constructed of as many smaller sections as may be desired.

The wooden frame or core not only serves 80 to stiffen and strengthen the door, but also serves to prevent it from warping—a difficulty heretofore experienced in doors made entirely of sheet metal.

I am aware that it is not new to make a 85 door of an interior core of wood and an outer covering or casing of sheet metal, entirely concealing the wooden frame or core.

What I claim is—

1. A fire-proof door for dwellings and the 90 like, composed of an interior wooden frame or core, two like or similar sections of sheet metal stamped, rolled, or pressed to represent paneling and provided with edge flanges, said metal sections being placed upon opposite sides of said wooden frame or core with their flanges fitting over and upon the edges thereof, and a metal strip h and screws i for securing said flanges in place, substantially 95 as described. 100

2. A fire-proof door for dwellings and the like, composed of a wooden frame or core provided with grooves f in its edges, two like or similar sections of sheet metal placed upon

opposite sides of said core or frame, and having flanges *e*, which are adapted to be bent or forced into the said grooves, and fastening devices for said flanges, substantially as described.

3. A fire-proof door for dwellings and the like, composed of a wooden frame or core provided with grooves *f* in its edges, two like or similar sections of sheet metal placed upon opposite sides of said core or frame, and having flanges *e*, which are adapted to be bent or forced into the said grooves, metal strips

placed in said grooves and upon the flanges to secure the same in place, and suitable fastening devices for said strips, substantially as described.

In testimony whereof I have hereunto set my hand this 27th day of February, A. D. 1890.

CHARLES E. RICHARDSON.
